[57] **CLAIM**

The ornamental design for the removable and adjustable mirror unit for facilitating alignment of trailer hookup, as shown and described.

DESCRIPTION

FIG. 1 is an isometric view of the removable and adjustable mirror unit for facilitating alignment of trailer hookup showing our new design on a reduced scale in position of use it being understood that the broken line illustration of the back end of a van and the front end of a trailer hitch is for illustrative purposes only and forms no part of the claimed design;

FIG. 2 is a top view thereof;

FIG. 3 is a bottom view thereof;

FIG. 4 is a right side view, the left side view being a mirror image thereof;

FIG. 5 is a back view thereof; and,

FIG. 6 is a front view of the invention.

FIG. 1

FIG. 2

FIG. 3

FIG. 4

FIG. 5

FIG. 6
